VEHICLE LIGHTING SYSTEM

John R. Haines, Tabernacle, N. J., assignor to
 Arrow Safety Device Company, Inc., Medford,
 N. J., a corporation of New Jersey

Application December 28, 1939, Serial No. 311,241

4 Claims. (Cl. 171—97)

This invention relates to a vehicle lighting system, particularly for the proper control of main and auxiliary headlights.

There has been introduced a type of lamp for use as a motor vehicle headlight in the form of an evacuated bulb containing filaments with the headlight lens formed integrally with the bulb and provided with a polished reflecting surface formed also on the bulb. An alternative type of headlamp comprises a bulb of more or less conventional form formed as a unit with a reflector and lens and adapted to be located as a unit in a suitable socket member mounted on the car. In both these forms of headlamps, one of the primary advantageous characteristics is that the reflecting surface is resistant to the corrosion which is so detrimental to headlamps of prior type. In the case of the former type of lamp, corrosion is practically non-existent, since the reflecting surface is hermetically sealed from air and moisture. In the latter form, suitable sealing greatly minimizes the damage from corrosion.

While new cars are provided with arrangements for carrying the types of sealed lamps just described in lieu of any headlamps of prior types, there are in use many automobiles carrying the old type headlamps subject to deterioration. Instead of resilvering the mirrors of such headlamps, it is considerably more advantageous to provide the new sealed type of lamp. However, this cannot be received in the conventional headlamp arrangements, and consequently provision must be made for carrying these sealed lamps as auxiliaries. This can be accomplished in many ways by the provision of mounting means for suitable sockets.

The matter of wiring up the new lamps, however, enters the picture, and it is desirable that the old lamps be retained in circuit to be used where relatively inefficient lighting may be desirable, as, for example, in city driving, or, as mere emergency lights in the event that the sealed type of lamps burn out or are damaged.

It is a broad object of the present invention to provide a switching arrangement designed for the alternative energization of the sets of lamps. Even more specifically, it is the object of the invention to provide for a complete arrangement in which dim and bright filaments may be selectively controlled, particularly to secure the common asymmetrical type of beam arrangement found desirable for country driving.

The above and other objects of the invention will be appreciated from the following descrip-

tion, read in conjunction with the accompanying drawing, in which:

Figure 1 is a diagram in the nature of a wiring diagram showing a type of switch capable of association with a foot operated switch and headlamp to effect the desired results. In this diagram the actual wiring is omitted for the purpose of clarity, the connections being illustrated by letters.

Figure 2 is a vertical sectional view taken on the plane indicated at 2—2 in Figure 1, showing the operation of the switch when it is lighting the headlamps.

In the diagram of Figure 1, there are indicated at 2 and 4, respectively, the right and left standard headlamps of an automobile. Each of these is provided with two filaments. In lamp 2 these are designated as RB and RD, representing the right bright filament and right dim filament, respectively, while in the case of lamp 4 they are designated as LB and LD, respectively, indicating the left bright and left dim filaments. The auxiliary headlamps of the sealed type are represented at 10 and 12. These contain corresponding pairs of filaments indicated by RB', RD', LB' and LD'. Parking lamps are indicated at 6 and 8, respectively, containing the filaments P. These lamps may be auxiliary lamps on the fenders, for example, or may be bulbs within the main headlamp, or may be provided by third filaments of the main headlamp bulbs. It will be understood that, in accordance with conventional fashion, one side of each of these filaments is grounded. The other side of each filament is connected to a correspondingly indicated switch element or a plurality of such elements, indicated in the central portion of Figure 1. In the present day cars, it is common to provide a switching arrangement for the conventional headlamps which will provide for the simultaneous lighting of both dim filaments of the headlamps, both bright filaments of the headlamps, or an asymmetrical beam arrangement providing for a dim beam which might meet an oncoming

vehicle, and a bright beam to illuminate the right hand side of the road. This latter type of arrangement is worked out differently in different cars. In some cars, for example, the headlamps are so arranged that the beams cross each other, i. e., the beam from the right hand headlamp illuminates the left hand side of the road, and that from the left hand headlamp illuminates the right hand side of the road. In such case, when the asymmetrical beam arrangement is desired, the right hand headlamp throws a

dim beam and the left hand headlamp a bright beam.

In another type of arrangement, the headlamps illuminate normally their respective sides of the road. However, the filaments in the left hand headlamp are so arranged that when the asymmetrical condition is desired, the beam from the left hand headlamp is directed toward the right so as to avoid the eyes of an oncoming driver.

It will be understood that the terms dim and bright are used herein in the sense of the effects of the beams as viewed by an oncoming driver. Actually, the beams in all cases may be of the same candle power, but effective brightness or dimness so far as the oncoming driver is concerned is secured by causing the beams to be directed either downwardly or, in the case of the last mentioned asymmetrical arrangement, toward the right side or left side of the road. Instead of speaking of the different possible arrangements, throughout this specification and claims, the terms dim and bright will be used in the sense indicated, and it will be obvious that the invention is applicable to any one of the particular systems for securing beams of varying intensities.

A source of current is indicated conventionally as a storage battery 14, which, of course, is connected in conventional fashion with the usual generator. A foot switch for controlling the dim or bright condition of the headlamps is indicated diagrammatically at 16 as providing for connection of the battery either to a pair of contacts D₁ and D₂ or a pair of contacts B₁ and B₂, the former indicating a dim condition and the latter a bright one. This switch will be understood to be of the conventional type actuated by a button so that each operation causes it to move from the dim to the bright position or the reverse. Since this switch is conventional, it need not be further described.

In accordance with the present invention, there is provided a rather elaborate switching arrangement comprising a knob 18 connected to a spindle 20, which is mounted in bearings (not shown) so as to be slideable and rotatable. The knob may project from the front of the dashboard, and the actual switch elements may be located behind the same. This spindle 20 carries cam elements 22 and 24 of the type which will be clear from Figures 1 and 2. These cam elements may cause contacts to be made either by lengthwise movement of the spindle or by its partial rotation.

Spring contact elements, insulated from each other, are provided, as indicated in the figures. Along the section line 2-2, for example, these comprise members 26 and 26', designed to engage members 28. All of these flexible members are mounted in a suitably insulated carrier. The elements 26 and 26' are joined by strips 28 of insulating material so as to move together when acted upon by the cam 22. Such switch constructions per se are well known, being used for multiple pole switching quite commonly in the radio art.

The various leads of the switch elements are lettered in Figure 1 to correspond to the terminals or filaments to which they are connected. The actual wiring is omitted from Figure 1 for purpose of clarity since, as will be evident, a showing of the wires would be quite complicated. Actually, of course, the connecting wires are carried in cables so that the wiring is simple.

The spindle 20 has four axial positions, indicated as off, parking, symmetrical and asymmetrical, in Figure 1. It also has right or left positions adapted for the selective control of the main or auxiliary headlamps, as will be evident from the figures.

When the spindle 20 is in the off position, cams 22 and 24 fail to engage any of the springs. Accordingly, all the lamps are out. When it is moved to the parking position, illumination of the parking lamps will be effected, irrespective of the right or left hand position of the spindle, because the contacts controlling the parking lamps are deflected to be engaged by cam 22. In this position, cam 24 does not engage any of the switch elements.

In the third symmetrical position, the cam 22 will engage either of the switch elements, D₁, and will correspondingly move the switch elements B₁. If the spindle is in the left hand position, this will mean that D₁ engages RD and B₁ engages RB. At the same time, the cam 24 will cause its switch element D₁ to engage LD, and B₁ to engage LB. In accordance with the convention already described, the elements D₁ and B₁ are connected to the poles D₁ and B₁ of switch 16. As a result of this, it will be evident that if the switch 16 is in the dim position, the right and left dim filaments of the main headlights will be illuminated. If the switch 16 is in the bright position, then the corresponding bright filaments will be illuminated. If the spindle is rotated to the right hand position, the corresponding filaments of the auxiliary headlights are lighted.

When the spindle is in its outermost asymmetrical position, the cam 22 will continue to engage the same switch elements as before, but the cam 24 will now engage one of the switch elements designated D₂B₂. In this case if the switch is in the left hand position, irrespective of the position of the switch 16, the left hand bright filament of the main headlights will be illuminated. If the switch 16 is in the dim position, the right hand dim filament will be lighted by the action of cam 22. On the other hand, if the switch 16 is in the bright position, the right hand bright filament will be lighted.

Corresponding limitations of the filaments of the auxiliary headlamps will occur if the switch 18 is turned to its right hand position.

It will be evident that if the asymmetrical condition is not required, simplification is possible by elimination of the asymmetrical position of the switch 18 and also by the elimination of the special contacts D₂ and B₂, which are, of course, connected together in the more complicated arrangement.

It will be obvious that the invention may be put into practice by the use of other types of switches, the equivalent of that illustrated.

What I claim and desire to protect by Letters Patent is:

1. A vehicle lighting system comprising at least two pairs of headlights, each of which headlights comprises a bright filament and a dim filament, a source of current, means comprising a single manually operable element for selectively controlling the flow of current from the source through the bright or dim filaments, and auxiliary means electrically in series with the first mentioned means and also comprising a single manually operable element for selectively controlling the flow of current to the headlights of one pair only or to the headlights of the other

pair only, so that the bright or dim filaments of either pair may be selectively illuminated.

2. A vehicle lighting system comprising at least two pairs of headlights, each of which headlights comprises a bright filament and a dim filament, a source of current, means comprising a single manually operable element for selectively controlling the flow of current from the source through the bright or dim filaments, and auxiliary means electrically in series with the first mentioned means and also comprising a single manually operable element for selectively controlling the flow of current to the headlights of one pair only or to the headlights of the other pair only, so that the bright or dim filaments of either pair may be selectively illuminated, said auxiliary means also controlling, through manipulation of its manually operable element, an asymmetrical condition of the headlights of either pair by effecting the flow of current from the source through the bright filament of one member of a pair and through the dim filament of the other member of the same pair.

3. A vehicle lighting system comprising at least two pairs of headlights, each of the headlights of at least one of said pairs comprising a bright filament and a dim filament, a source of current, means comprising a single manually operable element for selectively controlling the flow of current from the source through the bright or dim filaments, and auxiliary means electri-

cally in series with the first mentioned means and also comprising a single manually operable element for selectively controlling the flow of current to the headlights of one pair or to the headlights of the other pair only, so that the bright or dim filaments of at least one of said pairs may be selectively illuminated.

4. A vehicle lighting system comprising at least two pairs of headlights, each of the headlights of at least one pair comprising a bright filament and a dim filament, a source of current, means comprising a single manually operable element for selectively controlling the flow of current from the source through the bright or dim filaments, and auxiliary means electrically in series with the first mentioned means and also comprising a single manually operable element for selectively controlling the flow of current to the headlights of one pair only or to the headlights of the other pair only, so that the bright or dim filaments of at least one of the pairs may be selectively illuminated, said auxiliary means also controlling, through manipulation of its manually operable element, an asymmetrical condition of the headlights of at least one of said pairs by effecting the flow of current from the source through the bright filament of one member of the pair and through the dim filament of the other member of the same pair.
